WALL STRUCTURE

James E. MacDonald, Latrobe, Pa., assignor to
McFeely Brick Company, Latrobe, Pa., a cor-
poration of Pennsylvania

Application October 4, 1941, Serial No. 413,616

4 Claims. (Cl. 72—38)

My invention relates more particularly to furnace wall structures, such as open hearth furnaces, billet heating furnaces, etc., but it will be understood that it may be employed in constructing the walls of other structures.

In furnaces having brick arches which are subjected to severe heat and wide temperature changes, there are often many thousands of bricks placed on the arch, in straight courses. In some instances, the bricks of these straight courses are supported mainly by the arch, while in other instances metal hangers are provided, for the purpose of supporting the upper bricks and thus relieving the arch of their weight.

In the first instance, the spalling away of the arch in service causes the other bricks to fall into the furnace or slag pockets, as the case may be, thus requiring rebuilding of the entire wall. There is also danger of the arch failing, and allowing the wall to fall on workmen who may have entered the slag pockets of an open hearth furnace, for example, for the purpose of cleaning them or making repairs.

Metal hangers are not entirely satisfactory, because it is always necessary to have the iron framework of the furnace in perfect alignment to fit the hangers, and the hangers themselves must have proper alignment relative to the bricks. These conditions of alignment, even when corrected to furnace irregularities, will not remain so.

One object of my invention is to provide a furnace wall of such form that the bricks above an arch will be largely self-sustaining, thus not only preventing buckling down thereof when the arch is removed for repairs or becomes worn away, but avoid imposing on the arch a stress or weight that tends to cause spalling thereof.

Another object of my invention is to provide a wall of such form that it will in itself serve as an arch, although the bricks are laid in straight courses.

Still another object is to provide a wall of such form that certain courses may be made self-sustaining by the use of specially formed bricks and which will serve to also support upper courses of bricks of standard shape, so that the entire wall above an arch or in a blast furnace need not be formed of the special bricks.

Some of the forms which my invention may take are shown in the accompanying drawings wherein Figure 1 is a perspective view of a portion of a furnace wall embodying my invention; Fig. 2 is a view showing one of the bricks of this structure; Fig. 3 shows one of the side mar-

ginal bricks of Fig. 1; Fig. 4 is a sectional view through a portion of an open hearth furnace wherein my invention is incorporated; Fig. 5 is a longitudinal sectional view of a portion of a billet heating furnace or the like, showing my invention embodied in the wall above the door arch; Fig. 6 shows a modification of the structure of Fig. 1; Fig. 7 shows a modification of the form of brick shown in Fig. 2; Fig. 8 shows a wall formed of bricks of somewhat different form than those shown in Figs. 2 and 3; Fig. 9 is a perspective view of one of the bricks of Fig. 8, and Fig. 10 is a perspective view of my improved form of bricks as shaped to form a circular wall.

Referring first to Figs. 1 to 4, the structure comprises the conventional form of brickwork 14 and arch 15, which, in this instance, is shown as forming the upper portion of a port leading from an air slag pocket 16 to an air regenerator chamber 17 and checkerwork 18, this brickwork being placed between buckstays 19 placed at opposite sides of the port walls. These various parts may be of any well known form and detailed description thereof is unnecessary, the brickwork in Fig. 4 being shown on a reduced scale relative to Fig. 1.

In order to make the brickwork above the arch 15 self-sustaining, I employ bricks 20 and 21 of the forms shown in Figs. 2 and 3, respectively. The bricks 20 have edge surfaces 22 sloping upwardly from the mid plane thereof and edge surfaces 23 sloping downwardly from said plane, while the bricks 21 have a vertical edge face for abutting the buckstays and upwardly and downwardly sloping surfaces 24 and 25 that engage the surfaces 22 and 23 of adjacent bricks 20. Conventional filler bricks 26 are employed between the arch 15 and the upper brickwork.

It will be seen that the bricks of each vertical row are staggered or offset with respect to the bricks of the adjacent rows, so that the uppermost surface of each brick will be at the median planes of the bricks in the adjacent vertical rows. Each brick is therefore supported by its sloping surfaces 22 upon the sloping surfaces 23 of adjacent bricks, the marginal bricks 21 having their sloping surfaces 24 fitting against the sloping surfaces 23 of adjacent bricks and their surfaces 25 fitting against the surfaces 22 of adjacent bricks. In the present instance, the brickwork is shown as bonded in a direction transversely of the arch by making the wall thickness equal to the combined lengths of two bricks and employing half-length bricks 27 at the ends of each full-length brick which overlaps one-half of each

two adjacent full-length bricks. The spaces at the top and bottom of the wall which result from the vertical offsetting of the bricks 20 and 21 are filled by bricks 28 and 29 which are of one-half the thickness of the other bricks.

Where economy of construction is desired, that portion of the wall above the bricks 20 may be built with bricks of standard form as indicated at 31 in Fig. 4, although it will be understood that the entire furnace wall above the arch may be constructed of my specially formed bricks. The brickwork at 20 is not only self-sustaining, but will be of sufficient strength to withstand the weight of the entire wall above the arch 15, even though the arch be worn away or removed, because of the wedging force set up at the surfaces 22 and 23. The brickwork therefore cannot buckle. Furthermore, the arch 15 is relieved of the major portion of the weight, so that it will not be subjected to spalling through the crushing force of the brickwork above the arch, as frequently occurs. Also, workmen can enter the furnace to clean out the slag pocket without danger of the brickwork caving in on them through failure of the arch. Again, when the arch becomes worn through erosion, workmen can safely enter the slag pocket 16 to install a new arch, without the necessity of tearing down and rebuilding the entire wall. In former structures, while the furnace is in operation, badly-worn arches may remain intact by means of a fused bond with adjacent bricks. However, when the furnace is cooled during repairs, the brickwork contracts and breaks this fused bond—allowing the arch to cave in.

As shown in Fig. 4, my improved wall structure may be employed above the arch 32 that extends over the air slag pocket, my special brick structure being shown at 33 and the conventional brickwork at 34 for completing the wall. Similarly, the improved wall arrangement can be employed above the arch 35 that extends over the bulk-head 36, in this case the brickwork as shown above the arch in Fig. 1 being indicated generally by the numeral 37.

In Fig. 5 I show my invention applied to the side wall of an ordinary heating furnace such as a slab or billet heating furnace, which has a low arch 38 at the discharge door, and arches 39 at the check doors. These low arches 38 are usually formed of fire clay brick which tend to shrink and let the bricks fall out and, furthermore, are sometimes dislodged by the material or tongs being inserted into or removed from the furnace. In any event, the bricks 20 will remain in place when the arch fails, and the arch will not have to support the weight of the bricks 20.

Referring now to Fig. 6 I show a structure wherein the bricks 20 and 21 can be incorporated in a wall without the use of a conventional form of arch, the bricks being in themselves arranged to form a contour of generally arch form as indicated at 40. It will be seen that the bricks to each side of the vertical center line of the arch are in stepped relation to one another and that that side surface of each brick which is nearest to said center line is vertical instead of sloped, so as to provide ledges at 41. While these ledges are not essential to maintain the arch shape, they are desirable because they not only facilitate the building of the wall, but maintain the brickwork against slight sagging until the bricks have been expanded by the furnace heat, in the case of silica bricks, for example. Also, they prevent slight sagging or settling upon shrinkage of the

bricks when the furnace cools. The bricks 21 at each end of the wall are supported on an angle 41a that is bolted to the buckstays 19.

In Fig. 7 I show a brick 42 having the elongated shape of the bricks 20 to extend throughout any desired wall, but of a type known as metal case brick. It comprises a metal shell 43 filled with magnesite 44, the shell being open at its front and back. The magnesite filler will usually be in granular form chemically bonded and the bond increased in strength by the heat to which the brick is subjected in use.

These metal-clad bricks will be of particular utility when there are very high temperatures, as for example in the ports and downtakes of open hearth furnaces. Highly refractory material is required to withstand these high temperatures, but the more refractory materials such as magnesite do not have sufficient mechanical strength. In walls of bricks having the conventional metal shell for magnesite, at those ends of the bricks which are exposed to the heat there forms a fused or monolithic bonding of the metal, which gives increased mechanical strength. However, the fusing is not to a very great depth. By the use of metal case bricks of the special cross-sectional forms shown in my drawings, there is not only fusing of the metal at the inner ends of the bricks, but greatly increased mechanical strength throughout the entire length of the bricks and for the full thickness of the wall. My wall will, therefore, have much greater strength than walls constructed of the metal-faced bricks of conventional form.

In Fig. 8 I show a self-sustaining brick structure formed of bricks 45 and 46, which may be substituted for the bricks 20 and 21. A wall structure formed of these bricks is self-sustaining by reason of the fact that the edge surfaces thereof slope upwardly from the median plane of the brick, as shown at 47 and 48, and slope downwardly from such plane as shown at 49 and 50. The sloping surface 49 of each brick will fit against the sloping surface 47 of an adjacent brick, as indicated at 51, while the sloping surface 48 of each brick will fit against the sloping surface 50 of an adjacent brick, as shown at 52. The bricks are thereby firmly held or wedged in place with respect to one another, so that the wall is self-sustaining.

Referring now to Fig. 10, I show bricks 53 of cross-sectional form similar to that of the bricks 20, but so shaped that they can be employed in laying up a circular or curved wall. The bricks are of generally keystone shape (viewed in plan), in that they taper from their outer ends toward their inner ends. Their sloping surfaces 54 and 55 correspond to the surfaces 22 and 23 of the bricks 20.

I claim as my invention:

1. A wall structure having an upper portion comprising bricks each having its opposite edge surfaces above its median plane sloped upwardly in relatively flared planes and having the edge surfaces below its median plane sloped downwardly in relatively flared planes, the upwardly-sloped surfaces of each brick fitting between the downwardly-sloping edge surfaces of two adjacent bricks, and means for supporting the ends of said upper wall portion, an arch being formed intermediate the end supports by omitting bricks at the lower edge of the wall structure, at progressively higher planes, so that one-half of each of certain bricks at the arch pro-

jects below the adjacent brick next nearer to the vertical center line of the arch.

2. A wall structure having an upper portion comprising bricks each having its opposite edge surfaces above its median plane sloped upwardly in relatively flared planes and having the edge surfaces below its median plane sloped downwardly in relatively flared planes, the upwardly-sloped surfaces of each brick fitting between the downwardly-sloping edge surfaces of two adjacent bricks, and means for supporting the ends of said upper wall portion, an arch being formed intermediate the end supports by omitting bricks at the lower edge of the wall structure, at progressively higher planes, so that one-half of each of certain bricks at the arch projects below the adjacent brick next nearer to the vertical center line of the arch, a curved arch positioned beneath the said upper portion of the wall, means for

10 supporting the curved arch at its ends, and filler elements interposed between the top surface of the arch and the said upper wall portion, to provide a continuous face above the curved arch.

4. A wall structure having an upper portion 15 comprising bricks each having its opposite edge surfaces above its median plane sloped upwardly in relatively flared planes and having the edge surfaces below its median plane sloped downwardly in relatively flared planes, the upwardly-sloped surfaces of each brick fitting between the downwardly-sloping edge surfaces of two adjacent bricks, means for supporting the ends of 20 said upper wall portion, a curved arch positioned beneath said upper portion of the wall, means for supporting the curved arch at its ends, and filler elements interposed between the top surface of the arch and the said upper wall portion, to provide a continuous face above the curved arch.

JAMES E. MACDONALD.
